UNITED STATES PATENT OFFICE

164,109

EYE TESTING DEVICE

Charles A. Ellis, Southbridge, Mass., assignor to
American Optical Company, Southbridge,
Mass., a voluntary association of Massachusetts

Application February 16, 1951, Serial No. 14,249

Term of patent 14 years

(Cl. D57—1)

To all whom it may concern:

Be it known that I, Charles A. Ellis, a citizen of the United States of America, residing at Southbridge, in the county of Worcester and State of Massachusetts, have invented a new, original, and ornamental Design for an Eye Testing Device, of which the following is a specification, reference being made to the accompanying drawings, forming a part thereof.

Fig. 1 is a perspective view of an eye testing device embodying my new design; and

Fig. 2 is a side elevational view thereof.

The characteristic features of my new design are shown in full lines in the drawings.

I claim:

The ornamental design for an eye testing device, substantially as shown and described.

CHARLES A. ELLIS.
